(57) **CLAIM**

The ornamental design for a face plate for plumbing fixture, as shown and described.

DESCRIPTION

In a preferred embodiment, the nature of this product is as a flow distributor primarily useful for enabling a water spray from a plumbing fixture.

FIG. 1 is a right, top, front perspective view of a face plate for plumbing fixture embodying my new design;

FIG. 2 is a front elevational view thereof;

FIG. 3 is a top plan view thereof;

FIG. 4 is a bottom plan view thereof; and,

FIG. 5 is a left side elevational view thereof, the right side elevational view being a mirror image of the left side shown.
